UNITED STATES PATENT OFFICE.

ELIJAH McCOY, OF CARTHAGE, MISSOURI.

STEAM CANNING APPARATUS.

No. 926,588.

Specification of Letters Patent.

Patented June 29, 1909.

Application filed July 14, 1908. Serial No. 443,466.

To all whom it may concern:

Be it known that I, ELIJAH McCoy, a citizen of the United States, residing at Carthage, in the county of Jasper and State of Missouri, have invented a new and useful Steam Canning Apparatus, of which the following is a specification.

The invention relates to a steam canning apparatus.

10 The object of the present invention is to improve the construction of steam canners and cookers, and to provide a simple, inexpensive and efficient steam canning apparatus, adapted to scald fruit, vegetables, etc., in the preparation of the same for canning such goods, and capable also of simultaneously steaming and cooking fruit, vegetables, etc., after the same have been placed in the cans.

20 With these and other objects in view, the invention consists in the construction and novel combination of parts hereinafter fully described, illustrated in the accompanying drawings, and pointed out in the claims 25 hereto appended; it being understood that various changes in the form, proportion, size and minor details of construction, within the scope of the claims, may be resorted to without departing from the spirit or sacrificing 30 any of the advantages of the invention.

In the drawings:—Figure 1 is a perspective view of a steam canning apparatus, constructed in accordance with this invention. Fig. 2 is a simple longitudinal sectional view 35 of the same. Fig. 3 is a transverse sectional view, taken substantially on the line 3—3 of Fig. 2. Fig. 4 is a detail view of the metallic basket. Fig. 5 is a detail view of one of the removable inner holding trays.

40 Like numerals of reference designate corresponding parts in all the figures of the drawings.

The steam canning apparatus comprises in its construction a furnace 1, constructed 45 of sheet metal, or other suitable material and having vertical side walls 2 and 3 and vertical end walls 4 and 5. The furnace is provided with a horizontal bottom 6, which is supported above the floor, or other supporting surface by means of a plurality of legs 7, arranged in pairs and consisting of transversely disposed metallic bars 8, secured to and extending across the lower face of the bottom and having their terminals bent downwardly to form the legs 7. The lower ends 55 of the legs are bent outward horizontally to

form feet, as clearly shown in Fig. 3 of the drawings. The casing formed by the said side and end walls is divided by a horizontal partition 9 into upper and lower portions, 60 the lower portion constituting the furnace proper, and the upper portion forming a boiler and divided by a transverse vertical partition 10 to form a scalding vat 11 and a steam generating and cooking vat 12. The 65 lower portion of the furnace receives a horizontal grate 13, which is supported by horizontal side and end flanges 14 and 15 and by a lower vertical longitudinal partition 16, arranged centrally of the furnace and provided with upper and lower flanges 17 and 18, the lower flange being secured to the bottom of the furnace and the upper flange being arranged to support the grate beneath 70 the median line of the same. The flanges are 75 preferably formed of metallic strips, which are L-shaped in cross section to form attaching flanges, as clearly illustrated in Fig. 3 of the drawings. The furnace is provided in its end 5 above and below the grate with 80 openings 19 and 20 for the introduction of fuel and for the removal of ashes, and it is also equipped with an upper fuel door 21 and a lower door 22, which is arranged to cover the opening communicating with the 85 ash pit or space below the grate. The grate may be of any desired construction and various fuels may be employed, as will be readily understood, and the wall 4 is provided with a stove pipe hole 23, located at 90 the fire box or combustion chamber for the escape of the smoke and other products of combustion. A suitable stove pipe or stack 24 is connected with the furnace at the opening 23, an annular flange or collar 25 being 95 provided for the attachment of an elbow 26 at the lower end of the stove pipe 24.

The scalding vat or compartment 11 is extended above the steam generating and cooking vat or compartment 12, and it receives 100 a metallic basket 27, provided with a suitable handle 28 and having its side and end walls and its bottom constructed of spaced metallic strips or bars. The body portion 105 of the basket, which has downwardly tapered sides, extends from the bottom of the vat or compartment 11 to a bar adjacent to the upper edges of the same, and its handle 28 extends above the vat or compartment 11, as clearly shown in Figs. 1 and 2 of the drawings for enabling the basket to be easily removed from the apparatus. The open sides,

ends and bottom of the basket subjects its contents thoroughly to the scalding action of the hot water contained within the vat or compartment 11, which is designed to be 5 employed for scalding and cleaning vegetables, fruit and other goods in preparing the same for canning. The basket operates as a strainer to enable the scalded fruit, vegetables, or other goods to be lifted from the 10 boiling water of the vat or compartment 11 without removing or emptying the latter. As the vat or compartment 11 and the scalding basket are both open at the top, it will be apparent that the fruit, vegetables, or 15 other goods may be rapidly handled to scald them in the apparatus and to remove them therefrom.

The steam generating and cooking vat or compartment receives the fruit, vegetables 20 or other goods, which are contained in cans 29, arranged in trays 30. The apparatus may be constructed in different sizes and its capacity may be varied as desired. The trays of the cans are arranged in a vertical 25 series, the lower tray being placed upon a perforated support 31, and the other trays being placed upon the cans of the tray below them. By this construction and arrangement, the trays containing the cans 30 are arranged in spaced relation with each other and also with the bottom of the vat or compartment 12. The support 31, which is oblong, consists of a plate of sheet metal, or other suitable material, provided at inter- 35 vals with perforations 32 and having depending side and end flanges 33, which rest upon the bottom of the vat or compartment 12. The trays are provided in their bottoms with perforations 34, and they have 40 side and end walls 35. The perforations 34 of the trays correspond to and register with the perforations of the support 31, so that any one of the trays may be placed upon the support without closing or covering either 45 the perforations of such tray, or the perforations of the support. The trays are also provided at their ends with suitable han- 50 dles 35^a, adapted to enable the trays to be conveniently handled both in placing them in and removing them from the apparatus and also in conveying them from one point or place to another.

The steam is rapidly and effectively generated by means of a longitudinal series of 55 transversely disposed approximately U-shaped tubes, composed of two sides and a connecting bottom portion or bend, and extending downward from the horizontal partition 9 to the grate 13 and resting upon the latter. By extending the tubes downward 60 from the horizontal partition to the grate, the former is relieved of the weight of the tubes, which by resting upon the grate constitutes spaced supports for the horizontal partition.

65 This also arranges the lower portions of the

tubes directly within the fire and secures a maximum heating capacity. The sides of the water tubes are located at opposite sides of the median line of the furnace, and their upper ends, which are open, pierce the horizontal partition 9 and communicate with the space above the same. The ends of the pipes are threaded for the reception of the upper and lower nuts 37, arranged in pairs and engaging the upper and lower faces of 75 the horizontal partition. The tubes, which are located within the fire box or combustion chamber, subject comparatively small quantities of water to the intense heat of the fire contained within the furnace, and steam is 80 thereby rapidly produced for steaming and cooking the contents of the cans.

The steam discharged from the pipes 36 is confined within the apparatus by means of a removable receiver or dome 38, composed of 85 vertical side and end walls and an arched or dome-shaped top 39 and adapted to be placed over the trays of the cans after the latter have been arranged within the apparatus. The receiver or steam dome is provided at the 90 top with a handle 40 for enabling it to be readily placed over and removed from the cans, and it is also equipped with a pivoted closure 42, adapted to cover or partially cover the opening 41. When the closure is 95 arranged to entirely cover the opening 41, it is secured in such position by a resilient catch 43, mounted on the top of the steam dome or receiver adjacent to the free end of the closure 42. The opening 41 and the 100 closure form a safety valve to prevent the apparatus from being injured by a too rapid generation of steam.

The apparatus is provided at the upper portion with spigots or faucets 44 and 45, 105 communicating, respectively, with the vats or compartments 11 and 12 and adapted to enable the water to be drawn off from the apparatus when the same is not in use.

Having thus fully described my invention, 110 what I claim as new and desire to secure by Letters Patent, is:—

1. A steam canning apparatus including a furnace provided with a casing having a horizontal partition dividing the casing into upper and lower portions, a grate arranged within the lower portion of the casing, and a vertical partition dividing the upper portion of the casing into a scalding vat and a steam generating and cooking vat, a steam dome or receiver fitting within and extending above the steam generating and cooking vat, a support arranged within the steam generating and cooking vat and provided with perforations and having depending side and end 120 flanges, and can receiving trays also arranged within the steam generating and cooking vat and covered by the steam dome or receiver.

2. A steam canning apparatus comprising a furnace including a casing having a hori- 130

zontal partition dividing the casing into upper and lower portions, a grate arranged within the lower portion of the casing, and substantially U-shaped water pipes composed of two sides and a connecting bottom portion and extending downward to and resting upon the grate and constituting spaced supports for the horizontal partition, the upper terminals of the sides of the tubes 5 10 15 20
